(57) **CLAIM**

The ornamental design for a combined displacement pump and displacement pump housing, as shown and described.

DESCRIPTION

FIG. 1 is a front, right side isometric view of a combined displacement pump and displacement pump housing in accordance with the new design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a front, right side isometric view of the housing portion thereof;

FIG. 8 is a top plan view of the housing portion thereof;

FIG. 9 is a bottom plan view of the housing portion thereof;

FIG. 10 is a right side elevational view of the housing portion thereof;

FIG. 11 is a front elevational view of the housing portion thereof; and,

FIG. 12 is a rear elevational view of the housing portion thereof.

The portions of the combined displacement pump and displacement pump housing shown in broken lines in FIGS. 1-5 and 7-12 are included for illustrative purposes only and form no part of the claimed design.

1 Claim, 8 Drawing Sheets
